R. T. ST. JAMES

DETECTOR FOR WIRELESS SYSTEMS

Filed April 10, 1922

Inventor
Robert T. St. James

By Clarence E. Melville Atty

UNITED STATES PATENT OFFICE.

ROBERT T. ST. JAMES, OF CHICAGO, ILLINOIS, ASSIGNOR TO CHICAGO MINIATURE
LAMP WORKS, OF CHICAGO, ILLINOIS, A CORPORATION OF ILLINOIS.

DETECTOR FOR WIRELESS SYSTEMS.

Application filed April 10, 1922. Serial No. 551,149.

To all whom it may concern:

Be it known that I, ROBERT T. ST. JAMES, a citizen of the United States, and a resident of Chicago, county of Cook, and 5 State of Illinois, have invented certain new and useful Improvements in a Detector for Wireless Systems; and I do hereby declare that the following is a full, clear, and exact description thereof, reference being had to the accompanying drawings, and to the letters of reference marked thereon, which form a part of this specification.

This invention relates to improvements in what are commonly known as detectors in 15 the wireless telegraph and telephone art and consists of the matters hereinafter described and more particularly pointed out in the appended claims.

The object of the invention is to provide a 20 detector of great efficiency and of maximum sensitiveness. This and other objects and advantages of the invention will appear and be fully pointed out as I proceed with my specification.

25 In the drawings:

Figure 1 is a side elevation of a detector tube embodying my invention;

Figure 2 is a perspective view on an enlarged scale, showing the wiring of my improved detector;

Figure 3 represents a side elevation of the cold electrode of the detector, viewed in the plane indicated by the line 3—3 of Fig. 1;

Figure 4 is a diagrammatic view representing a wireless receiving system including my improved detector.

Referring to the drawings:—10 indicates the antenna of a wireless system and 11 indicates the air core transformer, the primary 40 11^a of which is connected to ground at 12 and the secondary 11^b of which is included in the indicator receiver circuit 13,—said receiver being shown in this case as a telephone receiver 14.

45 15 indicates the detector. This is the usual exhausted glass tube or bulb 16, having sealed therein three conducting members or electrodes; namely, an electrode 17, which is to be heated; a normally cold electrode 18; and a control electrode 19 interposed between the two and commonly known as a grid in detectors of the kind heretofore used. 50 20 indicates the battery for heating the electrode 17, and 21 the battery in circuit

between the cold electrode 18 and the telephone receiver 14. The circuits described constitute a simple tube circuit and are as usual and familiar,—their relation and connection forming no part of the present invention.

55 Referring now to the detector itself:—The cold electrode 18 is in the form of a cylindrical sleeve,—being a thin metal plate bent into cylindrical form. (See Fig. 2). The hot electrode 17 is a filament loop disposed approximately in the line of the central axis of the cold electrode 18.

60 The control electrode 19 is in the form of a helical coil surrounding the hot electrode filament 17 and supported at its bottom, but entirely free of support at its top. The wire of the coil is made heavy enough so 65 that the several convolutions or loops of the coil will stand, one above the other, in their preliminary, determined, vertically spaced, relation without danger of contact between the parts of proximate convolutions or loops and the resultant short-circuiting of one or more of said loops. The control 70 coil is also rigid enough so that it will stand with its central axis vertical or substantially coincident with the central axis of the cold electrode, cylindrical plate 18, and so 75 that there is no danger of the control coil falling against or contacting with the plate 80 or with the filament and thereby temporarily bridging and short-circuiting the loops or convolutions of the coil.

85 For the best results and preferably, the coil 19 and cylindrical plate 18 are so proportioned in diameter that the periphery of the coils is equidistant from the axis of the filament and from the inner surface of said plate.

90 It appears that higher potentials can be built up on a helical coil, with its one end free and with its adjacent convolutions or loops free from contact with each other or from supporting connections adapted to bridge or short-circuit them. However this 95 may be, I have found that with a coil of the kind, the added sensitiveness intended to be produced by the well-known grid heretofore used, is still further increased and raised to a maximum.

100 As shown in the drawings and preferably, the bottom end of the wire forming the coil 19 is bent down to provide a short depend-

ing stem 19^a which is secured in a short tube 19^b sealed with the conductor 19^c, which connects with the coil, in the glass sealing tube 22, which carries in a familiar manner the several conductors leading to the electrodes of the detector. The tube 19^b is clinched or collapsed and welded upon the stem 19^a of the coil 19 so as to securely grip it and support and hold the coil 19 in proper vertical position.

The cold electrode, cylindrical plate 18 is connected to and supported by a forked wire arm 23. This consists, as shown, of two wires twisted together at their bottom ends 15 to provide a stiff stem 23^a, which is sealed in electrical connection with the conductor 23^b, leading to the cold electrode in the sealing tube 22. Said wires are spread apart above the stem 23^a to provide the tines or prongs 20 23^c of the fork, which extend up to points at or adjacent to the top of the cylindrical plate 18, where their ends are attached, as by welding, to said plate. As shown, said prongs are hooked over the top edge of the 25 plate, with their ends welded to the inner surface of said plate. A narrow metal tongue 18^x, cut along the bottom edge of the plate 18 and bent about the stem 23^a, provides, with the ends of the prongs of 30 the forked wire arm 23, a three-point support for the cylindrical plate. This has been found to be amply sufficient to hold the cold plate in proper, erect position 35 with its axis vertical or coincident with the axis of the coil 19, and provides a simple and

efficient support for the plate which is thereby cheaply and quickly applied.

While in describing the invention I have referred to several details of mechanical construction and arrangement, it is to be understood that the invention is in no way limited thereto, except as pointed out in the appended claims.

I claim as my invention:

1. In a detector comprising an exhausted vessel, the two main electrodes therein, and a control electrode intermediate the said main electrodes, an insulating sealing plug for said vessel containing the conductors leading to said electrodes, a short metal tube sealed with one conductor in said plug and projecting above said plug, and the control electrode having a stem depending into said metal tube, said tube providing a support for and being secured to the stem of said control electrode.

2. In a detector including an exhausted vessel, a conductor-carrying sealing plug for said vessel, a plate element in said vessel, an electrically conductive support for said plate element, consisting of a stem sealed in said plug and of laterally spaced, upwardly extending prongs attached to said plate element near its top, the plate element having a tongue formed at its bottom edge and bent about said stem.

In testimony that I claim the foregoing as my invention, I affix my signature this 5th day of April, A. D., 1922.

ROBERT T. ST. JAMES.
